UNITED STATES PATENT OFFICE.

THOMAS ALEXANDER BOYD, HAROLD ARTHUR BOYD, AND JAMES BOYD, OF GLASGOW,
SCOTLAND.

SPINDLE OF SPINNING, TWISTING, AND LIKE FRAMES.

Application filed May 7, 1926, Serial No. 107,442, and in Great Britain June 2, 1925.

This invention refers to spinning, twisting and like frames in which the spindles and bearings are adapted to be inverted wholly or partially for the purposes of doffing, with the object of keeping the oil from escaping from such spindles and bearings when they are inverted.

According to this invention a spinning spindle is mounted in a self-contained socket 10 which is provided with a receptacle placed above the level of the oil supply in the said socket and so arranged that on the spindle and socket being wholly inverted or partially inverted for the purpose of doffing a 15 bobbin from the spindle, the oil shall flow into the said receptacle and be retained there during doffing operations.

Another part of our invention refers to the spindle itself. On the spindle an inverted 20 cup is mounted above the spindle bearing which cup receives any oil which may flow from the spindle or socket when these are inverted. Spindles of this description may be used alone for the purposes described or 25 in combination with the spindle socket having an oil receptacle above referred to.

The accompanying drawing illustrates in sectional view one form of the invention.

In giving a practical illustration of our 30 invention as applied to the spindles of a worsted spinning frame, we employ a rotating spindle 1 and bobbin carrier 2 mounted in bearings and traversed up and down while working in a usual manner. To the 35 bobbin carrier 2 referred to half a revolution is given when it is required to remove the full bobbin from its spinning position to its doffing position. On the said bobbin carrier 2 we mount a self-contained spindle socket 3 and in it we mount the spinning spindle 1 40 carrying a spinning bobbin 4. On the same axis as the spinning spindle 1 at a convenient distance above the spindle, we mount a spinning flyer 5 which is supported in a top 45 rail 6, the flyer legs hanging downwards and driving the spindle 1 by means of a cross member on the spindle. The flyer 5 is driven by a tape from a tin cylinder in a usual manner. The spindle socket 3 referred to has a hole right through. At the 50 top end 3¹ of the hole 3² we mount an internal tube 7 which serves as the bearing for the spindle 1. In the spindle socket 3 we form an oil space 3³ around the internal tube 7, which oil space we fill to a suitable height

from the bottom of the spindle socket 3. On the sides of the internal tube 7 we form openings 7¹ above the footsteps 7² to permit the oil to enter the internal tube 7 and lubricate the spindle 1. The oil space above the 60 openings referred to forms a chamber of sufficient capacity to receive all the oil from the spindle socket 3 when the spindle 1 and its socket 3 are inverted. At the bottom end of the spindle socket 3 we screw an oil cup 8 which can be removed for cleaning and which is filled with oil to give the requisite quantity of oil. On the spindle 1 above the internal tube 7 we mount an inverted oil cup 9. When the spindle 1 and socket 3 are inverted this oil cup 9 will receive any oil that may flow downwards along the spindle. On the spindle and socket being turned from their inverted to their working position the oil from the oil cup 9 on the spindle will 70 flow down the spindle and the oil from the receptacle afore referred to will flow to the bottom of the spindle socket and through the openings in the internal socket will lubricate the spindle. On the upper end of the spindle socket 3 we mount a spring catch 10 to keep the spindle 1 in its position when the spindle and socket are inverted.

Having now particularly described and ascertained the nature of our said invention and in what manner the same is to be performed, we declare that what we claim is:—

1. In spinning, twisting and like machines in which the spindles which carry the bobbins or the like are wholly or partially inverted for the purpose of doffing, means carried by the spindle for catching any oil which may flow from the spindle during doffing, said means being adapted to return such oil to the spindle socket when the spindle is turned back to running position.

2. In spinning, twisting and like machines in which the spindles which carry the bobbin or the like are wholly or partially inverted for the purpose of doffing, a self-contained spindle socket, in combination with an internal tube mounted within said spindle socket, serving as a bearing for the spindle, and a footstep at the base of said internal tube, in which the end of the spindle rests, said spindle socket and said internal tube together forming a chamber above the level of the oil supply for the footstep adapted to receive and retain the oil when the spindle and self-contained socket are in-

verted, and adapted to return the oil to the footstep when the spindle is turned back to running position.

3. In spinning, twisting and like machines in which the spindles which carry the bobbin or the like are wholly or partially inverted for the purpose of doffing, an inverted cup carried by the spindle for catching any oil which may flow from the spindle 10 during doffing, said inverted cup being adapted to return such oil to the spindle socket when the spindle is turned back to running position.

4. In spinning, twisting and like machines in which the spindles which carry the bobbin or the like are wholly or partially inverted for the purpose of doffing, an inverted cup carried by the spindle for catching any oil which may flow from the spindle 15 during doffing, said inverted cup being adapted to return such oil to the spindle socket when the spindle is turned back to running position.

socket when the spindle is turned back to running position, a self-contained spindle socket, an internal tube mounted within said spindle socket serving as a bearing for the 25 spindle, and a footstep at the base of said internal tube in which the end of the spindle rests, in combination with a flyer for driving said spindle through a detachable connection said spindle socket and said internal 30 tube together forming a chamber above the level of the oil supply for the footstep adapted to receive and retain the oil when the spindle and self-contained socket are inverted and adapted to return the oil to 35 the footstep when the spindle is turned back to running position.

In testimony whereof we have signed our names to this specification.

THOMAS ALEXANDER BOYD.

HAROLD ARTHUR BOYD.

JAMES BOYD.
